UNITED STATES PATENT OFFICE

113,642

DESIGN FOR A LIGHTING FIXTURE OR SIMILAR ARTICLE

Lemuel L. Stewart, Elkhart, Ind., assignor to The Adlake Company, a corporation of Illinois

Application December 31, 1937, Serial No. 74,029

Term of patent 14 years

To all whom it may concern:

Be it known that I, Lemuel L. Stewart, a citizen of the United States of America and a resident of Elkhart, county of Elkhart, and State of Indiana, have invented a new, original, and ornamental Design for a Lighting Fixture or Similar Article, of which the following is a specification, reference being had to the accompanying drawing, forming a part thereof, wherein

Fig. 1 is a front elevational view of a lighting fixture or similar article showing my new design;

Fig. 2 is a bottom plan view; and

Fig. 3 is a sectional view taken on the line 3—3 of Fig. 2, the retaining ring being shown broken in the middle to indicate that a portion of the ring has been omitted from the drawing.

I claim:

The ornamental design for a lighting fixture or similar article, substantially as shown.

LEMUEL L. STEWART.
